UNITED STATES PATENT OFFICE.

JAMES D. FLOOD, OF CHICAGO, ILLINOIS.

RADIATOR.

Application filed September 23, 1920. Serial No. 412,277.

To all whom it may concern:

Be it known that I, JAMES D. FLOOD, a citizen of the United States, residing at 5414 Eastview Park, Chicago, in the county of Cook and State of Illinois, have invented a new and useful Improvement in Radiators, of which the following is a specification.

This invention relates to improvements in radiators, and more especially to that type of radiator adapted for use in connection with motor vehicles for cooling the water, or other fluid used as a cooling medium around the cylinders of an internal combustion or other engine.

15 In that form of device embodying the features of my invention shown in the accompanying drawings, Figure 1 is a view in front elevation of my improved radiator, Fig. 2 is a sectional view taken as indicated 20 by the line 2 of Figure 3, and Fig. 3 is a vertical sectional view taken as indicated by the line 3 of Fig. 2.

As shown in the drawings, the radiator comprises an upper water tank 5, a lower 25 water tank 6, vertical water tubes or pipes 7 connecting the tanks, and cooling fins or plates 8 through which the tubes 7 pass. The tank 5 is provided with a suitable inlet pipe 9, and likewise the tank 6 is provided with a suitable outlet pipe 10.

As clearly shown in Fig. 2, the vertical water tubes 7 are arranged in eighteen rows of four each, with one extra tube at each end to fill in the corners. Each row of four 35 tubes is arranged in a vertical plane lying obliquely to a vertical plane intersecting the radiator at right angles. The distance between the rows is sufficient, so that the front tube of one row does not "cover" the back tube of the adjacent row. In other words, there is not more than one tube lying in any vertical plane intersecting the radiator at right angles.

The cooling fins or plates 8 are formed of 45 thin sheet metal or other material adapted to conduct heat from the tubes 7 and radiate the same to the air. They are provided with holes adapted to accommodate the tubes 7, and are held in place by soldering or by 50 other suitable means. The fins or plates 8 are obliquely arranged with respect to a hor-

izontal plane with their rear edges somewhat higher than their front edges. As shown in Fig. 3, the front side of the radiator is to the left. In the use of the radiator, air 55 is passed through the same, between the tanks 5 and 6, from the front to the rear as indicated by the arrows in Fig. 3. This circulation of air is maintained by the forward movement of the radiator on a vehicle, 60 and also may be maintained or assisted by a suitable fan well known in the art, (not shown on the drawings). The passage of air referred to is also shown by the arrows in Fig. 2.

It will be noted that the arrangement of the tubes 7 in slanting rows of four each (see Fig. 2) permits each tube to be struck directly by the incoming air. In other words, no tube shields, shadows, or blankets 70 to another tube from the incoming air. By this arrangement of the tubes, their cooling will be facilitated.

It will be noted also that the cooling plates or fins 8, being obliquely arranged with their 75 rear edges higher than their front edges, will direct the incoming air upwardly, as indicated by the arrows in Fig. 3, thereby causing the air passing through the radiator to take a longer course than if it went 80 through in a horizontal plane, with the result that it will cool a greater surface of the tubes 7. By this arrangement of the fins 8 also, a greater combined surface of all such fins is obtained with a smaller number. In other words, by arranging the fins obliquely, a greater cooling surface with a smaller number of fins is obtained, than if the fins were arranged horizontally.

While I have shown and described certain embodiments of my invention, it is to be understood that it is capable of many modifications. Changes therefore in the construction and arrangement may be made without departing from the spirit and scope 90 of the invention as disclosed in the appended claim, in which it is my intention to claim all novelty inherent in my invention as broadly as possible in view of the prior art.

It should also be noted that the inclination of the fins exposes the top surfaces more flatly to the incoming air, thus causing

the fins to cool faster than if merely their edges were exposed to the incoming air.

What I claim as new, and desire to secure by Letters Patent is:

5. In a radiator, substantially vertical water tubes arranged in slanting rows with a sufficient distance between each two adjacent

rows, so that the front tube of one row will not blanket the back tube of the adjacent row.

In witness whereof, I have hereunto set my hand and seal this 17th day of September, 1920.

JAMES D. FLOOD. [L.S.]
